UNITED STATES PATENT OFFICE.

KARL BURGHART AND GEORG BÜHLER, OF VIENNA, AUSTRIA.

SELF-REGULATING ELECTRIC STRIKING MECHANISM FOR CLOCKS.

Application filed November 13, 1922. Serial No. 600,592.

To all whom it may concern:

Be it known that we, KARL BURGHART and GEORG BÜHLER, citizens of the Republic of Austria, residing at Vienna, in the Republic of Austria, have invented certain new and useful Improvements in Self-Regulating Electric Striking Mechanism for Clocks, of which the following is a specification.

This invention relates to a self-regulating electric striking mechanism for clocks, said striking mechanism having ratchet wheels which are only axially journaled and cams and contact disks fixed or attached thereto arranged so as to regulate the number of strokes.

Owing to this arrangement a special driving mechanism for the striking mechanism may be dispensed with. Furthermore the arrangement permits altering the position of the hands attached to the ratchet wheels by a simple shifting without moving the hands from one intermediary stage to the next and so on. The rigid attachment of the cams and contact disks to the ratchet wheels secures the automatic and correct adjustment of the strokes.

The cam and the contact disk for striking the quarters of the hour and the respective disks for striking the hours, are arranged opposite to each other between the ratchet wheels, whereby the contact for striking the hours and the quarters is made in the simplest manner by contact bars or the like.

The ratchet wheels are arranged in such a manner, that the seconds wheel is placed between the minute wheel and the hour wheel, so that the striking mechanism for striking the hours and the quarters is controlled from the seconds wheel.

In the accompanying drawings which show by way of example one form of the invention,

Fig. 1 is an end view and Fig. 2 a side elevation both showing the disks for the clockwork, striking mechanism and alarm apparatus, said disks being arranged on the axle of the hands. There is also shown the pawl and contact bar for the striking mechanism.

Figs. 3 to 8 show front and rear views of some of the disks. The minute wheel 5, seconds wheel 6 and hour wheel 7 are arranged on the axle 1 and are connected to their respective hands by sleeves 2, 3 and 4 surrounding each other. Each of the seconds wheel 6, minute and hour wheels 5 and

7 have 60 teeth with which a pawl 8 cooperates. The latter is provided with three steps and the middle part working on the seconds wheel projects so far that the outer steps which are to engage the minute wheel and hour wheel respectively, generally are not active. In order to effect step by step movement of the minute wheel 5 the gearing of the seconds wheel 6 is provided with a deeper recess 9 at one point between two adjacent teeth into which the pawl 8 projects with its middle part in such a way that also the stepped part working on the minute wheel engages with the same causing it to step forward for one tooth. The shorter shoulder of pawl 8 allotted to the hour wheel 7 meanwhile is idle. The minute wheel 5 is provided with 5 deeper recesses 10 and if the recess 9 coincides with one of the recesses 10 the pawl 8 engages all the recesses on the corresponding wheels and causes them to step forward for one tooth. Therefore once in a minute the minute wheel and the minute hand connected thereto is moved for 6 degrees and every 12 minutes the hour hand is moved likewise.

For stepping forward the seconds wheel for one tooth in every second a single pawl 8 is sufficient, if a half seconds pendulum is used. If clocks with seconds pendulum are used, two pawls must be provided both arranged to rotate about a centre of motion outside of the three wheels. In this case one of the pawls 8 is provided with three steps as described, whereas the other pawl 8' only works on the seconds wheel and therefore is only provided with one step.

The striking mechanism consists of two hollow coils not shown in the drawings, each provided with an iron core sliding upwards as soon as the circuit is closed and actuating the striking lever of a gong. For closing the circuit disks 11 and 12 provided with contact parts, are fixed on both surfaces of the seconds wheel. On each of the contact disks 11 and 12 a contact bar 13 slides, which upon rotation of the disks is repeatedly brought into contact with the parts of the disks carrying the current whereby the circuit for the striking mechanism is closed. The contact bars 13 are guided by cams 14 and 15 of insulating material connected with the minute and hour wheel respectively. The quarter striking cam 14 connected with the minute wheel 5 is four stepped, the step for striking the first quarter having the

largest, the step for striking four quarters having the smallest diameter. The contact disk 12 arranged on the seconds wheel has a contact part 20 so shaped that a contact is made by the contact bar 13 once, twice, three or four times successively according to the position of the quarter striking cam 14. As this should only take place every 15 minutes the minute wheel 5 carries on the surface opposite to the cam 14 a control disk 17 with four contacts 18 set at right angles to each other, which close the circuit just before each period of striking. As the four contacts 18 arranged on the minute wheel 5 allow closing of the circuit every fifteen minutes only, the circuit is closed for one minute at the longest, because the contact at the contact element 18 is broken after this time has elapsed. The circuit is only closed when one of the contact elements 18 and the arm 13 cooperating with the contact piece 20 close the circuit. During this minute, however, the contact between 13 and 20 is only effected for a part of this time, viz, for the time in which the seconds wheel 6 passes through an arc corresponding to the contact piece 20. The drawing shows contact piece 20, for the sake of clearness, on an enlarged scale. The real length of it corresponds to the arc run through in four seconds. The hour cam 15 connected with the hour wheel 7 consists of twelve sections 19 of decreasing diameter on which the second contact bar 13 impinges successively and makes contact from one to twelve times according to the height of the steps with a contact piece 16, arranged on the contact disk 11 and shaped appropriately.

In order to ensure contact making at the first stroke the forward ends of the contact pieces 16 and 20 of the contact disks 11 and 12 are advantageously of a somewhat larger diameter than the largest diameter of the respective cams 14 and 15.

The alarm apparatus is switched in by making contact between a button 21, Fig. 7, on the hour wheel and a conducting spring 22 fixed on the alarm disk which is mounted on the axle 1. The alarm device is preferably provided with a special current supply by means of a slip-ring 24 fixed on the disk 23 of insulating material, on which a brush, not shown, slides. The signal after being released continues to sound for twelve minutes viz until the contact between the button 21 and spring 22 is interrupted by the hour wheel being stepped forward for one tooth but it may also be stopped in the meantime by a circuit breaker.

The current for driving the clock can be taken from any power-main, choking coils being inserted if necessary.

The above described mechanism operates as follows: The wheels 5, 6 and 7 are actuated by means of the pawls 8, 8', which are

controlled by the pendulum, not shown, in such a manner that the wheel 5 will execute one rotation within one hour, the wheel 6 within one minute and the wheel 7 within twelve hours. Every fifteen minutes the closing of the circuit is permitted by means of the contact elements 18 which are placed on wheel 5; according to the relative position of the cam 14, on wheel 5, the contact arm 13 which is in abutment with the contact piece 20, actually produces the closing of the circuit for one to four seconds, which circuit is, however, interrupted every second by the pendulum so that the quarter striking mechanism executes one to four strokes. According to the position of the cam 15, which is placed on the hour wheel 7, one to two strokes are made by the hour striking mechanism. When the hour wheel 7 has moved so far that its contact button 21 is just opposite the spring 22 on the alarm disk 23, the special alarm circuit is closed, whereby the alarm signal is given.

Current passes through the control arm contacts 18, through minute wheel 5, the body of the mechanism, wheel 6 to contact pieces 16 and 20.

When these contact pieces are engaged by their respective arms 13 current passes from these arms to solenoids striking respectively quarter hours and hours, and thence by any suitable return wire.

A separate circuit for the alarm enters through slip ring 24, and passes by spring 22 when in contact with button 21 to wheel 7 and clock mechanism and thence to any type of electrically operated alarm.

What we claim is:

1. In a clock striking mechanism, a pair of dial train wheels, a contact member on one wheel, a control cam on the adjacent wheel and a pivoted arm between the wheels whose engagement with the contact member is controlled by said control cam.

2. In a clock striking mechanism, a dial train comprising co-axial dial ratchet wheels, one or more of which wheels have at intervals interdental spaces of greater depth than the other interdental spaces of the wheels, an actuating pawl common to all of said wheels, a contact member on one wheel and a control cam on an adjacent wheel, and an arm between the wheels whose engagement with said contact member is controlled by said cam.

3. In a clock mechanism, a dial train comprising a plurality of co-axial dial ratchet wheels, an actuating pawl common to said wheels, a manually set contact spring and a contact on one of said wheels moved past said spring for closing an alarm circuit.

4. In a clock mechanism, a dial train comprising a plurality of co-axial dial ratchet wheels, an actuating pawl common to said wheels, a manually set disk having

a slip ring thereon and a contact spring on said disk and electrically connected to said ring, and a contact on the hour ratchet wheel arranged to move under said spring and close circuit during the period between two successive steps of said wheel.

5. In a clock mechanism, a dial train comprising co-axial hour, seconds and minute ratchet wheels having equal numbers of teeth, the seconds ratchet wheel being arranged between the other two wheels, the seconds wheel having a deep interdental space and the minute wheel having five such spaces, an actuating pawl common to said wheels, a pair of contacts carried by the seconds wheel control cams carried by the hour and minute wheels and contact arms for closing circuit through said contacts and controlled by said cams.
- 10 6. In a clock mechanism, a dial train comprising a plurality of co-axial dial ratchet wheels, a driving pawl common to said wheels and arranged to step said wheels at different intervals of time, contacts carried by one of said wheels, control cams carried by the other of said wheels, and a pair of

contact arms each arranged to co-operate with a contact and a cam.

7. In a clock mechanism, a dial train comprising a plurality of co-axial ratchet wheels, a driving pawl common to said wheels and arranged to step said wheels at different intervals of time, contacts carried by one of said wheels, control cams carried by the other of said wheels, a pair of contact arms each arranged to co-operate with a contact and a cam, and a control circuit closing means co-operating with one of said wheels.

8. In a clock striking mechanism, a dial train comprising dial ratchet wheels, a pawl common to said wheels and arranged to engage the wheels at different intervals of time, and means to step one of said wheels between the driving intervals of said pawl.

In testimony whereof we affix our signatures in presence of two witnesses.
